UNITED STATES PATENT OFFICE.

FILO S. STEVENS, OF ASHVILLE, NEW YORK.

PICK.

1,148,633.

Specification of Letters Patent.

Patented Aug. 3, 1915.

Application filed March 4, 1914. Serial No. 822,382.

To all whom it may concern:

Be it known that I, FILO S. STEVENS, a citizen of the United States, residing at Ashville, in the county of Chautauqua and 5 State of New York, have invented certain new and useful Improvements in Picks, of which the following is a specification.

This invention relates to an improved pick, and the principal object of the invention is to provide a pick in which the handle and head are so constructed that the head may be readily removed from the handle for sharpening or for the purpose of replacing a different type of pick head, and 15 to provide an improved type of pawl for releasably holding the pick head in place, the pawl and pick head being so constructed that the head will be tightly wedged in place.

20 Another object of the invention is to provide a pawl which will be very strong and durable and which will not be liable to break or work loose.

Another object of the invention is to so 25 construct the pocket in which the pawl is pivotally mounted that the spring which yieldably holds the pawl in the normal position will be securely held in place.

This invention is illustrated in the accompanying drawings wherein—

Figure 1 is a view in elevation showing the pick head in the handle with the pawl removed; Fig. 2 is a section taken along the line 2—2 of Fig. 1 with the pawl in place; 35 Fig. 3 is a perspective view of the pawl; Fig. 4 is an elevation of the central portion of the pick head.

The pick head 10 has its outer face provided with a centrally located cut-out portion forming abutment shoulders 11 which are positioned upon opposite sides of the handle when the pick head is in place and serve to prevent longitudinal movement of the pick head. Upon the side of the pick head notches 12 are formed, the inner walls 13 of the notches being inclined as shown in Fig. 4 so that the pawl will have a tendency to move the pick head toward the outer end of the handle and cause the outer end of the handle to be seated between the abutment shoulders 11. The handle 14 has its outer end portion provided with a transversely-extending opening 15 which forms the pocket through which the pick head passes 55 and is also provided with a longitudinally-

extending recess 16 forming a housing or chamber in which the pawl 17 is pivotally mounted. In the bottom of the chamber 16 there is formed a well 18 which receives the spiral spring 19. From an inspection of 60 Fig. 2 it will be readily seen that the bottom of the chamber 16 is cut at an incline so that the pawl may be rocked upon its pivot pin 20 a sufficient distance to move its arms 21 out of engagement with the pick 65 head. These arms 21 which extend through the slots 22 have their free end portions provided with inwardly extending heels 23 which extend through the notches 12 to removably hold the pick head in place. It 70 should be noted that the ends of the arms are cut at an incline conforming to the incline of the inner walls 13 by notches 12 so that when the spring moves the pawl to its locked position, the arms of the pawl will 75 move the pick head to a position in which the abutment shoulders 11 will engage the end of the pick head. It should also be noted that this pawl by fitting into the notch 12 will prevent longitudinal movement of 80 the pick head.

The operation of this pick is very simple. When it is desired to insert the pick head, the pawl is moved to raise the arms thus permitting the pick to be passed into the opening 15. After the end of the pick has been inserted in the opening between the arms, the pick head can then be moved through the opening until the notches 12 reach the 90 heels 23. These heels will then drop into the notches and will move them outwardly to the position shown in Fig. 1 with the outlet end of the pick handle positioned between the abutment shoulders 11. By having the handle fit between the abutment shoulders, the 95 strain is partially removed from the heels 23 and therefore when using the pick, there is no danger of the heels being broken. When it is desired to remove the pick head to sharpen the same or to insert a pick head of a different size or type, the pawl is moved to raise the arms and the pick head can then be easily withdrawn.

There has thus been provided an improved pick in which the pick head is removably connected with the handle and in which the pick head will be securely held in place. There has also been provided an improved fastening means for the pick head which is so constructed that the pick head 110

will be prevented, from working loose and which will move the pick head to such a position that the outer end portion of the handle will fit between the shoulders formed upon the pick head thus preventing the securing means from being broken when the pick is in use.

What is claimed is:

1. In a tool of the character described a handle provided with an opening and with a recess formed in one side of the handle and communicating with said opening, the bottom of said recess having a well formed therein, a cutting element passing through said opening and having its outer face provided with abutments positioned upon opposite sides of said handle and having its inner face provided with notches having inclined inner walls, a pawl pivotally mounted in said recess and provided with arms extending into said opening and having their free ends provided with inclined inner ends and with heels extending into the notches of said cutting element, and a spring mounted in

said well and engaging said pawl to yieldably hold the same in a locked position.

2. In a tool of the character described a handle provided with a transversely extending cutout, a head extending through said cutout and provided with notches in one side face having inclined inner walls forming cam surfaces, abutment shoulders extending from the opposite wall of said head for engaging opposite sides of said handle, a pawl carried by said handle and provided with teeth passing into said notches and engaging the inclined inner wall thereof for moving said head into a position to bring said abutment shoulders into engagement with said handle, and means for releasably holding said pawl in an operative position.

In testimony whereof I affix my signature in presence of two witnesses.

FILO S. STEVENS.
